UNITED STATES PATENT OFFICE.

JAKOB EMIL KIRBERG, OF PHILADELPHIA, PENNSYLVANIA, ASSIGNOR TO
THE HENSEL, COLLADAY COMPANY, OF PENNSYLVANIA.

DESIGN FOR TRIMMING.

SPECIFICATION forming part of Design No. 33,272, dated September 25, 1900.

Application filed August 11, 1900. Serial No. 26,658. Term of patent 14 years.

To all whom it may concern:

Be it known that I, JAKOB EMIL KIRBERG, a subject of the Emperor of Germany, residing in the city and county of Philadelphia, State of Pennsylvania, have invented and produced a new and original Design for Trimming, of which the following is a specification, reference being had to the accompanying drawings, forming part thereof.

The leading features of my design for trimming is a body of serpentine form and groups of puffs thereon, the different members of the latter being on opposite edges of said body, said groups alternating with plain bends on said body.

Figure 1 represents a side elevation of a piece of trimming embodying my design. Fig. 2 represents a section thereof on line xx , Fig. 1.

In the drawings, A designates a piece of trimming consisting of the body B, of serpentine form, and puffs C, the latter being in groups, two members of which are on the bends of one edge of said body and two other members are on the bends of the opposite edge thereof. The bends between the groups or puffs are plain. The face of the body presents the appearance of parallel stripes.

Having thus described my invention, what I claim as new, and desire to secure by Letters Patent, is—

The design for trimming substantially as shown and described.

JAKOB EMIL KIRBERG.
